UNITED STATES PATENT OFFICE.

SHERMAN SHISLER, OF SALEM, OHIO.

DESIGN FOR A CLASP FOR THILL-TUGS.

SPECIFICATION forming part of Design No. 32,063, dated January 2, 1900.

Application filed December 6, 1899. Serial No. 739,444. Term of patent 14 years.

To all whom it may concern:

Be it known that I, SHERMAN SHISLER, a citizen of the United States, residing at Salem, county of Columbiana, State of Ohio, have invented and produced a certain new and original Design for a Clasp for Thill-Tugs, of which the following is a specification, reference being had therein to the accompanying drawings, in which—

Figure 1 is a perspective of my new and original design for clasps for thill-tugs. Fig. 2 is a side elevation of the same, and Fig. 3 is a vertical section through Fig. 2.

As shown in the drawings, the leading or material feature of my design consists of the parallel curved side bars A, joined at their opposite ends by means of straight bars B and provided at a point intermediate of their

ends with lugs C, carrying a cross-bar C'. Each of the bars B is provided with projections D, extending at an angle thereto. One of the end bars B is also provided with a plate E, the same being of rectangular outline and having a curved face E', extending transversely of the length of the plate. 20 25

Having described my invention, what I claim as new, and desire to secure by Letters Patent, is—

The design for a clasp for thill-tugs, as herein shown and described. 30

In testimony whereof I affix my signature in presence of two witnesses.

SHERMAN SHISLER.
